MACHINE FOR MANUFACTURING OF FISH NETS AND THE LIKE

Frithjof Heggland, Oslo, Norway, assignor to
 Kristiansands Fisegarnsfabrik A/S., Kristiansand S., Norway, a Norwegian concern

Application August 19, 1948, Serial No. 45,182
 In Norway May 10, 1947

3 Claims. (Cl. 87—53)

1

This invention relates to certain improvements in a machine, and a method for manufacturing fish nets or other similar net-work. The invention will be of value in connection with machines of the type in which a series of warp threads are fed to a knotting location or station, where the warp threads are knotted with weft threads that are supported by reciprocating shuttles, each of such shuttles carrying a spool for a single weft thread.

In a machine of this type a great number of shuttles is used, say some hundred, according to the width of the net to be produced. Knotting of the warp and the weft threads in these machines takes place just in front of the nose of a flat nozzle-like member or of a longitudinally slotted member through which the knotted net is successively retracted, the dimensions of the meshes formed being determined by a mechanism serving to retract the finally knotted net through the slotted member.

In manufacturing nets by means of a fish net machine of the type generally indicated above, the succession of operations are somewhat as follows:

The weft thread, which runs from the shuttle and forwards to the nose or inlet of the slotted member, is engaged by a hook whereby a loop is formed, the shuttle or shuttles at the same time being moved towards the front edge of the slotted member, and, accordingly, towards the location where knotting is effected. Another hook is passed forward through the loop formed in the weft, engages a warp thread and pulls a loop of the warp thread forward and moves the loop over the front end of the shuttle, where the loop is released. Then the weft and the warp threads are tightened, whereby the knotting operation is ended.

In the hitherto known machines of this type the weft thread is tightened as the shuttle returns to its initial position, so that the tightening takes place at an acute angle to the direction in which the knotted net is drawn backwards through the slotted member. Tightening of the warp is effected by retraction of the warp thread in some suitable manner. As soon as the knot has been made the knotted net is drawn rearwardly through the slotted member a distance suitable for the forming of a mesh of predetermined area, thereafter the above described sequence of operations is repeated.

It should be remembered that for each row of knots longitudinally of the fish net there must be provided a warp thread and a weft thread

5 with associated shuttle, and also that fish nets of usual dimensions often need several hundreds of such thread sets for their manufacture. Further, it should be remembered that the machine must be stopped each time one of the spools of weft thread is exhausted, for insertion of a new spool, and further, that the machine must be stopped if a thread has a defect, say a knot, or breaks. In view of these facts it is imperative 10 that the machine shall operate at the highest possible speed in the effective operation periods thereof. An increase of some few knots per minute thus will be very important as regards the efficiency of the machine and the cost of manufacturing nets. The main object of this invention is, therefore, to provide means enabling, inter alia, an increase in the speed of the machine.

In machines heretofore known of the type defined, the tightening of the weft thread takes 15 place at an angle to the loop which the hook has formed of the weft thread, or approximately in line with the net being produced. This causes a stress in the weft thread which makes possible a displacement of the knot position in the direction towards the shuttle, and this again makes a limitation of the tightening speed necessary. This 20 drawback is avoided in a machine according to the present invention, in which the tightening of the weft thread takes place in the direction of the weft loop and at a steep angle to the position of the net that is being made, whereby displacement of the knot position is avoided and the tightening speed may be increased.

Constructively this problem is solved in such 25 a manner that, in contrast to prior machines of the type defined, no retraction of the shuttle is made use of for tightening the weft loop. The shuttle is left at rest with its weft feed end near the knot or the front edge or nose of the slotted member during the tightening of the weft loop, and the said member and the hook holding the weft loop are then moved in the general direction of the axis of the weft loop, so that tightening 30 takes place by moving the knot position, instead of the knot position being at rest and the weft loop being tightened. This provides for the result desired and it becomes possible to increase the machine speed. Due to the fact that the slotted member and knot position are raised relatively to the position of the shuttle a further advantage is obtained, in that pulling out of the warp thread by means of a hook for releasing 35 the warp thread in the form of a loop above the shuttle takes place at a position situated higher than the shuttle, whereby it becomes far more

certain that said warp thread loop may easily slide over the shuttle.

Thus the invention relates to a machine for manufacturing fish nets or other similar network, by which warp and weft are fed to the machine proper, respectively from a suitable stock thereof and weft spooled up in shuttles, and in which knotting of warp and weft by means of hooks is effected immediately in front of a longitudinally slotted member, the shuttle during operation of the machine being reciprocated relatively to the slotted member through which the finished net is retracted. The machine is further characterized in that tightening of the weft, a loop of which has been placed around a loop of the warp, is effected during a step in which the shuttle is at rest with its end portion adjacent to the nose of the slotted member, and that said member and the shuttle are moved relative to each other along paths at a steep, preferably practically, right angle to each other, whereby the weft loop is tightened substantially at a right angle to the completed net.

In order that the invention may be better understood the same now will be described with reference to the accompanying drawings.

Figures 1, 2 and 3 diagrammatically illustrate the essential parts of a machine for producing nets; the machine parts shown comprise a unit including one shuttle only, and accordingly produces only one series of knots. In actual practice a machine for manufacturing nets would comprise a great number of such units placed side by side and cooperating.

Said three figures illustrate three different operation steps.

Fig. 1 shows the step in which the weft thread has been drawn up in the form of a loop and the warp thread, in the form of a warp loop, is being drawn through the weft loop.

Fig. 2 shows a step just after the weft loop has been drawn, and the warp loop is in position to be slid over the shuttle.

Fig. 3 shows the step in which the warp thread is being tightened and drawn under the shuttle.

Fig. 4 shows, on a larger scale, the positions of the weft and warp loops in Fig. 1; and

Fig. 5 shows the position of said loops in Fig. 2.

In Figs. 1, 2 and 3, the numeral 1 designates the frame of the machine. The frame carries rails or a table 2 on which reciprocates a carriage 3 supporting a shuttle 4 having a weft spool 5. The carriage 3 is reciprocated by means of an angular arm 6 having at one end a roller 7 which is guided by a cam disc 8.

On a shaft 9 is tiltably supported a member 10 carrying a flat nozzle-like or longitudinally slotted member 11, through which slotted member the completed net 12 is drawn to suitable storing cylinders (not shown) for the finished product. Member 10 also carries a guide 13 for the supply of warp thread 14 to the knotting location. The weft thread 15 from spool 5 is fed out through the shuttle 4.

The means provided for the formation of such loops as are necessary for producing knots adjacent to the front edge of the member 11 includes a hook 16 adapted to seize the weft and a hook 17 adapted to seize the warp thread. In the drawings, said hooks are indicated only diagrammatically, without connection with any driving means therefor, since such hooks and their operative movements are well known in the art.

The warp thread 14 is passed over suitable guide means, such as rods 18 and 19 of circular

cross section, attached to a tilttable arm 20 and over a similar rod 21 attached to a tilttable arm 22. Said arms 20 and 22 may be tilted by any suitable means for tightening or slackening the warp thread when the machine is operating.

The member 10 is tilted or rocked on the shaft 9 by means of links 23 and 24 and an arm 25. The arm 25 carries a roller 26 which operates on a cam disc 27 in such a manner that the member 11 and the guide 13 are raised and lowered as necessary during the operation of the machine.

With reference especially to Figs. 4 and 5 the formation of a knot for making a mesh will now be described.

In Figs. 4 and 5 the weft thread 15 is, as in Figs. 1-3, shown hatched, whereas the warp thread is illustrated by two parallel lines only.

After hook 16 has engaged the weft thread 15 and has pulled the latter upwards so that a weft loop 28 has been formed, hook 17 engages the warp thread and thus causes formation of a warp loop 29, which is drawn through the weft loop 28. In this position the weft thread 15 extending from the shuttle forms the loop 28, with portions of the thread crossed at point 30 to form a half-hitch, and continues to the previously completed knot 32, the point 30 being the location along the weft thread from the knot 32 where the next knot is formed.

The next operative step now is to tighten the weft loop 28. In machines of the defined type heretofore known, this has been effected by reciprocating the shuttle to cause a stress in the weft thread 15 in the direction indicated by an arrow 31, whereby the knotting location is likely to be displaced along the warp loop 29, in the direction indicated by arrow 31.

According to the invention, this drawback is eliminated by holding the shuttle at rest, not reciprocating, during this step, but instead thereof, raising the knotting point 30 towards the hook 16, as illustrated on Fig. 5, and tightening the weft loop 28. By applying a stress in the direction indicated by arrow 33 the weft loop 28 is, according to the invention, tightened, the stress acting in the same linear direction as the general axis of the weft loop 28. This prevents a displacement of the knotting point 30 in the longitudinal direction of the warp loop, and secures or maintains the correct distance between the preceding finished knot 32 and the new knotting point 30.

Returning now to Figs. 1, 2, and 3, the operation of the machine may briefly be described as follows:

When hook 16 has engaged or hooked into the weft 15 and formed the weft loop 28, simultaneously as the carriage 3 is moving towards the member 11, hook 17 is moved through the weft loop 28, engages the warp thread 14 and forms the warp loop 29. Then the member 11 and hook 16 swing up to the position shown in Fig. 2, while the carriage 3 and shuttle 4 remain substantially stationary. Thus the weft loop 28 is tightened, see Fig. 5, and at the same time the warp loop 29 is pulled out from the hook 17 and is slid over the end 34 of the shuttle 4. By means of a wheel 35, having notches 36, the warp thread loop is moved under the shuttle 4, at the same time as the lower ends of arms 20 and 22 move away from each other, so that the warp is tightened and a knot is formed at 30.

Due to the fact that the member 11 and the guide 13 are situated on a higher level than the

shuttle 4 when the warp loop 29 is drawn out, the present construction gives the additional advantage that the warp loop takes an inclined position relatively to the shuttle and is readily slid over the shuttle end 34. In known machines the said loop first had to be passed over the middle portion of the back of the shuttle.

I claim:

1. In a machine for making knotted fish nets and other knotted nets from warp and weft threads, including a slotted member through the slot of which the net is retracted as formed, a shuttle carrying a weft thread, means for reciprocating the shuttle in a path toward and away from the net inlet portion of said slotted member during the operation of the machine, means for forming a loop in the weft thread extending from the completed net to the shuttle, means for forming and carrying a loop of the warp thread through the loop in the weft thread and around the shuttle, means for maintaining the shuttle in a stationary position with respect to reciprocation adjacent the net inlet of said slotted member while the warp loop is being carried around the shuttle, and means for effecting relative movement of the shuttle and the net inlet portion of said member in a direction at a steep angle with re-

spect to the path of reciprocation of the shuttle, thereby tightening the weft loop around the warp loop.

5 2. A machine as claimed in claim 1, characterized in that said last-mentioned means includes means for effecting said relative movement during the movement of the warp thread through the weft loop.

10 3. A machine as claimed in claim 1, characterized in that said last-mentioned means includes means correlated with the means for reciprocating the shuttle and adapted to move the inlet portion of said member and the threads carried thereby in a direction at substantially a right angle to the path of reciprocation of said shuttle while the shuttle is in substantially said stationary position.
